UNITED STATES PATENT OFFICE.

THOMAS CHRISTOPHER FLEMING, DECEASED, LATE OF VANCOUVER, BRITISH COLUMBIA, CANADA, BY CORDELIA DELPHINE FLEMING, ADMINISTRATRIX, OF VANCOUVER, CANADA.

DESIGN FOR A COMBINED CABINET AND REFRIGERATOR.

55,998.

Specification for Design.

Patented Aug. 10, 1920.

Application filed September 20, 1919. Serial No. 325,258. Term of patent 3½ years.

To all whom it may concern:

Be it known that THOMAS CHRISTOPHER FLEMING, a subject of the King of Great Britain, formerly residing in Vancouver, in the Province of British Columbia, Dominion of Canada, did during his lifetime invent a new, original, and ornamental Design for a Combined Cabinet and Refrigerator, of which the following is a specification, reference being had to the accompanying drawing, forming part thereof.

The drawing is a front elevation of the combined cabinet and refrigerator showing my new design.

What is claimed is:—

The ornamental design for a combined cabinet and refrigerator, substantially as shown.

In testimony whereof I have hereunto subscribed my name.

CORDELIA DELPHINE FLEMING,
Administratrix of Thomas Christopher Fleming, deceased.
